UNITED STATES PATENT OFFICE.

ALFRED A. BRIGGS, OF NEW YORK, N. Y.

FLUSH-TANK FIXTURE.

Application filed February 3, 1922. Serial No. 533,801.

To all whom it may concern:

Be it known that I, ALFRED A. BRIGGS, a citizen of the United States, and a resident of New York, county of Bronx, and State 5 of New York, United States of America, have invented certain new and useful Improvements in Flush-Tank Fixtures, of which the following is a specification.

This invention relates to flush tank fixtures and particularly to the valve mechanism of such fixtures.

One of the objects of the invention is to provide a tank fixture of the character described that is simple in construction, comprises few parts and may be economically 15 manufactured.

Another object of the invention is to provide a fixture that is positive and quiet in operation and in which the parts are so 20 constructed and arranged that they will not be thrown out of adjustment in use.

Another object of the invention is to provide a construction that is rugged and will operate effectively and quietly without the 25 use of packings, washers or similar devices.

Further objects of the invention will appear from the following specification taken in connection with the drawings which form a part of this application and in 30 which—

Fig. 1 is a sectional elevation of a flush tank having a fixture constructed in accordance with the invention mounted therein, this view being taken substantially on line 35 1—1 of Fig. 2.

Fig. 2 is a top plan view of the construction shown in Fig. 1.

Fig. 3 is a sectional elevation taken through a portion of the valve mechanism 40 and showing one of the valves in open position and

Fig. 4 is a sectional elevation of the valve mechanism taken substantially on line 4—4 of Fig. 2.

The invention may be briefly described as 45 comprising a fixture mounted in a flush tank and having a U-shaped flush or outlet pipe of the usual construction and a casing mounted in the tank and, in the particular embodiment shown, secured to the outlet pipe. The casing is divided into two vertical sections, the upper section forming the supply chamber having a water inlet and the lower section being subdivided into two 50 chambers, each having a water outlet, one

leading to the tank and the other leading to the outlet leg of the U-shaped flush pipe. The connection to the flush pipe is so constructed and arranged that a conical spray will be introduced into the outlet leg of the 60 pipe. A pair of valves is provided for controlling the ports between the upper chamber and the two outlet chambers and one of these valves is manually controlled and the other valve is controlled by the water level 65 in the tank. The heads of the valves are conical and seat in conical seats, no packings being used. Further details of the invention will be explained in the following description.

In the drawings, I have shown a flush tank 10 having secured thereto a U-shaped siphon or flush pipe having its inlet leg 11 disposed adjacent the bottom of the tank and having its outlet leg 12 extending 75 through the bottom of the tank and secured thereto.

The leg 12 of the outlet or flush pipe is interrupted at 13 and a casing 14 is secured to this portion of the leg 12.

The casing 14 comprises an upper chamber 15 and a pair of lower chambers 16 and 16^A, the chamber 15 and chambers 16 and 16^A being connected by ports 17 and 17^A having conical seats. A water inlet pipe 18 85 is secured to the casing and communicates with the upper chamber 15 and a water outlet pipe or feed pipe 19 for the tank is secured to the casing and communicates with the lower chamber 16^A and as shown in Fig. 90 1 this pipe extends to a point adjacent the bottom of the tank whereby the water fed through this pipe to the tank will stir up any residue or dirt at the bottom of the tank and will tend to keep the tank free from 95 such matter.

As shown particularly in Figs. 3 and 4, the casing has formed on its lower section a pair of downwardly extending sleeves 20, the lower ends of these sleeves being closed 100 by plugs 21 having restricted openings 22 therein. In each of the sleeves 20 is positioned a valve stem 23 of a valve having a conical head 24 adapted to seat in one of the ports 17 connecting the upper and lower 105 chambers of the casing. Each valve stem is provided with a plurality of grooves 25 forming water seals.

One of the valves has its stem engaged by an end 26 of a bell crank lever, the other 110

arm 27 of the lever being connected by a link 28 to a lever 29 which extends through the tank and is connected to a suitable actuating chain or handle.

5 The other valve stem is connected by an end 30 to a bell crank lever, the other end of this lever having secured thereto a rod 31 and on this rod is adjustably mounted a float 32 of the usual construction. This adjustment of the float provides for the use of the mechanism with different water pressures. An arm 33 is also secured to the rod 31 and limits the downward movement thereof. The valve actuating ends 26 and 30 of the 10 bell crank levers are disposed in slots 34 formed in the valve stems and sufficient clearance is provided to permit the free action thereof.

20 The chamber 16 has formed thereon a conical portion or nozzle 40 communicating with the leg 12 of the flush pipe at the interrupted portion 13 thereof and this nozzle directs the conical spray into the leg 12 thereby inducing and starting the flow of 25 water therethrough, this flow after being started continuing by the usual siphon action.

20 In order to always maintain a water seal in the toilet trap the chamber 16^A is also connected to the outlet leg 12 by means of a pipe 41 and a small stream of water will continue to flow into this pipe even after the flush tank has been emptied.

35 In order to permit the entrance of air to the leg 11 of the flush pipe before the water has been drawn out sufficiently to admit air through the open lower end of this pipe I have formed in this leg a slot 42.

40 The method of assembling the valves will be clear from the showing in Fig. 4, wherein in the pipe 18 is shown as provided with an enlarged end 43 which is screwed into the upper wall of the casing, this end of the pipe being formed slightly larger than the head 45 24 of the valve. To permit the assembling of the other valve a plug 44 is screwed into an opening on the upper wall of the casing and this opening is also of such dimension that the valve head 24 may be inserted there- 50 through.

55 When the valves are moved to open position as shown in Fig. 3 the upward movement of the valve will cause water to flow into the lower end of the sleeves 20 through the restricted openings 22 and this water upon the return movement of the valve forms a cushion to prevent any noise when the valve is closed. In order to admit more water to the lower ends of the sleeves, each 60 sleeve has formed in its wall a slot 45 which is uncovered by the valve stem as the stem is raised.

65 The operation of the construction will now be briefly set forth. The normal water level in the tank is indicated by the dot and dash

lines in Fig. 1. When the tank is to be emptied the lever 27 is actuated, thereby raising the valve 24 controlled thereby and opening the port 17 between the chambers 15 and 16. This admits water from the pipe 18 and 70 chamber 15 to the chamber 16 and from this chamber the water will pass in a conical spray through the nozzle 40 thereby starting the flow of water through the outlet leg 12 of the flush pipe. After this flow has been started it will continue by siphon action until the tank is emptied. Upon the release of the lever 27, the water pressure in the chamber 15 will close the valve controlled by lever 27 but the other valve will be opened by the 75 downward movement of the float and rod 31. This will permit the flow of water through the casings 15 and 16^A to the pipe 19 and through this pipe to replenish the supply in the tank. When the water has again reached 80 the level indicated, the valve controlled by the float will be automatically closed.

85 During this entire operation water will flow through the pipe 41 and into the flush pipe thereby insuring a water seal in the 90 trap of the toilet and preventing the upward escape of gases. The water in the lower ends of the sleeves 20 will form a cushion for the return movement of the valve stems and valves thereby effecting a quiet operation thereof.

95 From the above description it will be seen that the fixture is very simple and rugged in construction and that the parts are so constructed and connected together that 100 they will be maintained in their proper adjustment and will not require the usual constant adjusting and replacing of parts. Furthermore, it will be particularly noted that no packings or washers of any kind are 105 required.

110 Although one specific embodiment of the invention has been illustrated and described, it will be understood that the invention is capable of modification and that changes in the construction and in the arrangement of the various cooperating parts may be made without departing from the spirit or scope of the invention as expressed in the following claims.

115 What I claim is:—

1. In a flush tank fixture, a tank, an outlet pipe secured to the tank, a casing secured to and supported on the outlet pipe and having an inlet chamber and a pair of outlet chambers, ports between said first chamber and the pair of chambers, a pair of valves controlling said ports, an inlet pipe leading to the inlet chamber and outlet ports in said other chambers leading to 120 the outlet pipe and to the tank.

2. In a flush tank fixture, a tank, an outlet pipe secured to the tank, a casing secured to and supported on the outlet pipe and having a single chamber communicating 125

- with a pair of chambers, ports between the single chamber and the pair of chambers, a pair of valves controlling said ports, an inlet pipe leading to said single chamber, 5 outlet ports in said other chambers leading to the outlet pipe and to the tank, manually controlled means for actuating one of said valves and means controlled by the water level in the tank for controlling the other 10 valve.
3. In a flush tank fixture, a tank, an unobstructed U-shaped outlet pipe having one leg adjacent the bottom of the tank and the other leg extending through the bottom 15 of the tank and means surrounding the pipe for directing a converging spray under pressure from outside of the pipe into the outlet pipe at an unrestricted portion thereof.
4. In a flush tank fixture, a casing having a pair of sections arranged one above the other, ports connecting said sections, an inlet pipe secured to the upper section, downwardly seating valves for said ports, outlet 20 ports in the lower section, manually operable means for raising one of said valves and means controlled by the water level in the tank for raising the other valve, said valves being closed by the pressure of the water in 25 said upper section of the casing.
5. In a flush tank fixture, a casing having an inlet chamber, and a pair of outlet chambers, the inlet chamber and outlet chambers being arranged one above the other, ports 30 having conical seats connecting said inlet and outlet chambers, an inlet pipe secured to the upper chamber, downwardly seating conical valves for said ports, outlet ports in the lower chambers, manually operable 35 means for raising one of said valves and means controlled by the water level in the tank for raising the other valve, said valves being closed by the pressure of the water in 40 said upper section of the casing.
6. In a flush tank fixture, a casing having a pair of sections arranged one above the other, the upper section having one chamber and lower section having a pair of chambers, ports connecting said upper chamber 45 and lower chambers, an inlet pipe secured to the upper chamber, downwardly seating valves for said ports, outlet ports in the lower chambers, actuating means for raising said valves, said valves being closed by the 50 pressure of the water in said upper section of the casing and hydraulic means for cushioning the closing movement of said valves.
7. In a flush tank fixture, a casing having a pair of sections arranged one above the other, the upper section having one chamber and lower section having a pair of chambers, ports connecting said upper and lower chambers, an inlet pipe secured to the upper 55 chamber, downwardly seating valves for said ports, outlet ports in the lower chamber,
- bers, actuating means for raising said valves, said valves being closed by the pressure of the water in said upper section of the casing, and hydraulic means controlled by the valve movement for cushioning the 70 closing movement of said valves.
8. In a flush tank fixture, a casing having a pair of sections arranged one above the other, ports having conical seats and leading from the upper section to the lower section, 75 an inlet pipe connected to the upper section, outlet pipes connected to the lower section, a pair of valves having conical heads adapted to seat in the ports, manually operable means for lifting one of said valves and 80 means controlled by the water level in the tank for lifting the other valve, the valves being closed by the pressure of the water thereon.
9. In a flush tank fixture, a tank, a U- shaped outlet pipe therein having an inlet end disposed adjacent the bottom of the tank and an outlet leg extending through the wall of the tank, a casing, a water inlet pipe secured thereto, means for conducting a spray 90 of water from the casing to the outlet leg of the U-shaped pipe and independent means for conducting water from the casing to said leg of the outlet pipe.
10. In a flush tank fixture, a tank, a flush pipe connected thereto, a casing having a pair of sections arranged one above the other and having a pair of ports establishing communication between said sections, a pair 95 of sleeves formed on the casing and extending downwardly from the lower section, and upwardly opening valves for said ports having stems mounted in said sleeves and control means for said valves.
11. In a flush tank fixture, a tank, a flush pipe connected thereto, a casing having a pair of sections, arranged one above the other and having a pair of ports establishing communication between said sections, a pair 100 of sleeves formed on the casing and extending downwardly from the lower section and having restricted openings in the lower ends thereof, and upwardly opening valves for said ports having stems mounted in said sleeves and control means for said valves.
12. In a flush tank fixture, a tank, a U- shaped outlet pipe therein having an inlet end disposed adjacent the bottom of the tank and an outlet leg extending through the 110 wall of the tank, a casing, a water inlet pipe secured thereto and an outlet nozzle on said casing connected to and surrounding the outlet leg of the U-shaped pipe and constructed and arranged to conduct a conical 115 spray of water to said pipe from outside of the pipe at an unrestricted portion thereof.
13. In a flush tank fixture, a tank, a U- shaped outlet pipe therein having an inlet end disposed adjacent the bottom of the tank 120

and an outlet leg extending through the wall of the tank, a casing surrounding the outlet leg of the U-shaped pipe and connected thereto near the upper end of said leg at an unrestricted portion thereof, a water inlet pipe connected to the casing, said casing and pipe being constructed to form an outlet

nozzle arranged to conduct a converging conical spray downwardly toward the longitudinal axis of the pipe.

10

In witness whereof, I have hereunto set my hand this 31st day of January, 1922.

ALFRED A. BRIGGS.
